UNITED STATES PATENT OFFICE.

CHARLES L. VAN INWAGEN, OF RUTHERFORD, NEW JERSEY, ASSIGNOR TO WESTERN ELECTRIC COMPANY, INCORPORATED, OF NEW YORK, N. Y., A CORPORATION OF NEW YORK.

WRENCH.

Application filed January 5, 1922. Serial No. 527,075.

To all whom it may concern:

Be it known that I, CHARLES L. VAN INWAGEN, a citizen of the United States, residing at Rutherford, in the county of Bergen, State of New Jersey, have invented certain new and useful Improvements in Wrenches, of which the following is a full, clear, concise, and exact description.

This invention relates to tools and particularly to spanner wrenches, and has for its main object to provide certain improvements therein whereby such tools are prevented from becoming inoperative should the longitudinal pin or pins used in such devices break due to any overstress or defects in the structure of said pins.

In connection with mechanical distributing systems it is necessary that retaining screws or bearing caps employed therein must serve not only as a binding medium between two or more parts, but in most cases their heads must present a sufficiently uniform bearing surface. This latter feature is accomplished by having the screws counter-sunk in the parts with which they are employed. To remove such screws requires the use of a wrench of a particular structure, which in general, consists of a body with one or more pins extending therefrom to engage apertures in the heads of such screws, thereby forming a binding between said screws and wrench so that the screw is easily removed upon the application of a force to the body of said wrench. If for any reason a screw should become tightly lodged in its setting, undue stress would have to be employed to remove such a screw. This undue stress may cause the extending pin or pins to bend or snap off rendering the wrench itself useless for further operation. To supply a method whereby the "junking" of such wrenches upon the breaking of these pins becomes unnecessary and by which such wrenches in these emergencies are supplied with new pins by a simple mechanical operation, is therefore a principal object of this invention.

This object is accomplished by having the longitudinal pins removably engaged in magazines located in the body of the wrench and a set-screw arrangement to permit such pins to be removed and replaced by new pins, the set-screws holding the pins in a desired position.

In the accompanying drawing, forming a part of this specification and in which similar characters designate like parts throughout the several views, a clear conception of this invention in its preferred form is disclosed. Fig. 1 shows a sectional side elevation of the preferred form of this invention. Fig. 2 shows a view looking down upon Fig. 1. Fig. 3 is a transverse section on the line 3—3 in Fig. 1. Fig. 4 gives a view of the base of Fig. 1.

The tool is illustrated as having a metallic casing or body 1, with apertures or magazines 2, 2' and 3, 3' located therein. In the apertures 2, 2', which are cylindrical and short in length, are fitted bushings or bearing surfaces 4 and 4', having central apertures 14, 14' in alignment with the apertures 3 and 3'. These bushings or bearing surfaces 4, 4' are of a harder material than that of casing 1, so that said casing is relieved of the crushing effect of the pins 5, 5' thereon, when said casing is caused to rotate by a force applied to it, and the extending portions of pins 5, 5' are engaged with an article to be turned, pin 5 being located in apertures 3 and 14 and pin 5' in 3' and 14'. This force may be applied in any number of ways, a preferred form of which is the use of a stake or handle 6 located as shown in the hole 7 (and in a diametrically opposed hole not shown) in casing 1. It will be observed that the casing at 3—3 and in the neighborhood thereof is of a greater section than elsewhere. This is to provide room for the threaded cavities 8 and 8' and the set screws 9 and 9'. The hole 15 is provided so that caps having extended studs may be removed by the wrench, the studs fitting the said hole, and the extending portions 13, 13' engaging apertures in the bearing cap to be removed.

To remove a screw or bearing cap that is inaccessible to the ordinary type of wrench the extending portions 13, 13' of pins 5, 5' are set in grooves or holes in the screw head adapted to be used with such a wrench. The base 10 would then be flush with the head of the screw or bearing cap to be removed. A force of rotation is then applied to the casing or body 1 by turning the stake 6. Since the body 1 and screw head are bound together by pins 5, 5' the rotation of said body will also cause the screw to rotate and there-

2

by be removed or inserted as the case may be. If for any reason the extending portions 13, 13' of pins 5, 5' should break, the tool is withdrawn from the screw head, set screws 5, 9, 9' are loosened in the usual way thereby relieving the pins 5, 5' of the pressure exerted thereon by screws 9, 9' at the points 12, 12'. The loosening of the set screws 9, 9' allows a new pin or pin portions located 10 in the magazines 3, 3' to move down the magazines by gravity or other means, thereby providing new extending portions. When the pins are adjusted to extend a certain length from said magazine, the set screws 9, 15 9' are then tightened and contact is thereby made between pins 5, 5' and set screws 9, 9' at the points 12, 12', and the pressure thereby exerted when the set screws are driven home holds the pins 5, 5' in the desired position. The wrench is therefore again operable.

In the above description it is stated that new extending portions such as 13, 13' are provided when a new pin 5 falls in place 25 when relieved by set-screw 9. It is not to be understood that the magazine 2 must carry successive new pins or pin portions to replace any of the pins that become broken, but said magazine 2 may carry but one long 30 pin as shown in the drawing, so that when the end thereof breaks the single pin is simply moved further down the magazine until it again extends therefrom. Should the fracture be ragged the ends of the broken 35 pins may be filed or ground down until said pins conform to the receptacles in the screw head with which they are to engage.

What is claimed is:

1. A tool comprising a casing having longitudinal apertures extending therethrough, bushings to fit said apertures, each of said bushings being provided with an opening, pins adapted to fit said openings in said bushings, and adjustable means for retaining said pins in the openings of said bushings in a desired position.

2. A tool comprising a casing with a plurality of apertures located therein, bushings and pins adapted to fit said apertures, said bushings being in certain of said apertures, and said pins adapted to fit other of said apertures, and means for adjusting the position of said pins in said apertures.

3. A tool comprising a casing with a plurality of apertures and having a certain hardness, bushings to fit certain of said apertures, said bushings being of a harder material than that of said casing, an aperture in each of said bushings, pins slidably engaged in the apertures of said bushings, and means for retaining said pins in the apertures of said bushings in a desired position.

4. A tool comprising a casing with thread-

ed cavities circumferentially located therein 65 and with longitudinal apertures located in said casing, bushings adapted to fit certain of said apertures and having longitudinal openings in said bushings, pins fitting said openings, set-screws for said threaded cavities and engaging said pins to hold them in a predetermined position, and means located externally to said casing to impart rotational movement to said pins.

5. A tool comprising a casing with longitudinal apertures located therein and with a second set of apertures located at one end of said casing and superimposed on said longitudinal apertures, said second set of apertures being of larger cross-section and of shorter length than said longitudinal apertures, pins slidably fitting said longitudinal apertures, metallic bearing surfaces for said pins located at one end of said casing and of a harder material than said casing, 85 adjustable means for regulating the position of said pins in said longitudinal apertures, said pins extending from said apertures a certain length subject to a predetermined setting of said adjustable means, and means located on said casing to cause said pins to rotate concentrically with the axis of said casing.

6. A tool comprising a body portion having a plurality of longitudinal apertures located therein, certain of said apertures varying in cross-section throughout their length, pins adapted to extend through said apertures and substantially filling one portion thereof, and a member, provided with a hard bearing surface substantially filling the space between said pins and the wall of another portion of said aperture.

7. A spanner wrench comprising a casing with apertures in the end thereof, a bushing to fit each of said apertures having an opening therethrough, pins adapted to fit into the openings in said bushings and to extend beyond the end of said casing, and adjustable means for retaining said pins in a fixed position in the openings of said bushings.

8. A tool comprising a casing having longitudinal apertures extending therethrough, each of said apertures having an enlarged portion at one end of said casing, a bushing fitting into the enlarged portion of each of said apertures having a longitudinal opening therethrough, a pin fitting each of said openings and adapted to pass through the entire length of said apertures, and adjustable means including a set-screw for retaining each of said pins in a predetermined position in said openings.

In witness whereof, I hereunto subscribe my name this 3rd day of January, A. D. 1922.

CHAS. L. VAN INWAGEN.
